(57) **CLAIM**

The ornamental design for a prostate massager.

DESCRIPTION

FIG. 1 is a left side elevation view of a prostate massager, showing my new design, the right side elevation view being identical thereto;

FIG. 2 is a front end view thereof;

FIG. 3 is a rear end view thereof;

FIG. 4 is a top view thereof;

FIG. 5 is a bottom view thereof;

FIG. 6 is a left side elevation view thereof, with the internal probe removed, the right side elevation view being identical thereto;

FIG. 7 is a front end view thereof;

FIG. 8 is a rear end view thereof;

FIG. 9 is a top view thereof; and,

FIG. 10 is a bottom view thereof.
